US00D632267S

(12) **United States Design Patent**
Chen et al.

(10) **Patent No.:** US D632,267 S
(45) **Date of Patent:** ** Feb. 8, 2011

(54) **LIGHT EMITTING DIODE PACKAGING CARRIER**

(75) Inventors: **Chin-Ming Chen**, Hsinchu County (TW); **Chin-Chang Hsu**, Pingtung County (TW); **Hsuan-Chi Liu**, Hsinchu County (TW)

(73) Assignee: **Lextar Electronics Corp.**, Hsinchu (TW)

(**) Term: **14 Years**

(21) Appl. No.: **29/361,186**

(22) Filed: **May 6, 2010**

(30) **Foreign Application Priority Data**

Feb. 12, 2010 (TW) 99300769

(51) **LOC (9) Cl.** 13-03

(52) **U.S. Cl.** D13/180

(57) **CLAIM**

The ornamental design for a light emitting diode packaging carrier, as shown and described.

DESCRIPTION

FIG. 1 is a front perspective view of the packaging carrier showing our new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

FIG. 7 is a bottom plan view thereof wherein the broken lines form no part of the claimed design.
